INSTRUMENT AND CONTROL HOUSING FOR A VEHICLE LEVELING SYSTEM

Robert W. Hegel, Monroe, Mich., assignor to Monroe
Auto Equipment Company, Monroe, Mich.

Filed July 18, 1974, Ser. No. 489,757

Term of patent 14 years

Int. Cl. D10—05

U.S. Cl. D10—46

FIG. 1 is a right front perspective view of an instrument and control housing for a vehicle leveling system showing my new design;

FIG. 2 is a top plan view thereof;

FIG. 3 is a front elevational view thereof;

FIG. 4 is a right side elevational view thereof, the left side being a mirror image thereto;

FIG. 5 is a bottom plan view thereof.

I claim:

The ornamental design for an instrument and control housing for a vehicle leveling system, as shown and described.
